FOLDING LEG TABLE AND ACTUATOR MEANS

Benjamin E. Hood, South Fairlington, Va., assignor of one-tenth to Robert B. Harmon, Washington, D. C.

Application July 21, 1947, Serial No. 762,266

1 Claim. (Cl. 311—85)

1

This invention relates to tables with folding supports and has for a primary object to provide means for extending and retracting a plurality of supports for the table by the proper manipulation of any single support.

A more specific object is to provide a table having a simple manually operable means for extending and retracting two sets of paired legs supporting the table.

A further object is to provide a table in which either one of a pair of supporting legs may be moved to the extended or retracted position and thereby cause simultaneous and similar movement of a second pair of supporting legs.

Another object of the invention is to provide a table with a lever actuating means interconnected between two sets of paired supporting legs to permit all of the legs to be extended or retracted by the manual extension or retraction of any one of the legs.

A further object is to provide a table having extensible and retractable legs, the manual movement of any one of the legs imparting similar move to the other legs and having a positive means for locking the legs in whichever of the two extreme positions they are placed.

With the foregoing, and other objects in view, the invention resides in the following specification and appended claims, certain embodiments and details of construction of which are shown in the accompanying drawing in which—

Figure 1 is a partially cutaway view in perspective of the invention.

Figure 2 is a sectional view in side elevation showing the invention with the table legs extended.

Figure 3 is an enlarged sectional view in side elevation similar to Figure 2 but including a locking means.

Referring more particularly to the drawings, a table shown generally as 1 has a top 2 supported adjacent its periphery and on its underside by four interconnected beams 3. Rotatably mounted along their longitudinal axes and between two of the beams 3 are two cross arms 4 and 5. The cross arms 4 and 5 are preferably provided with steel bearing rods 6 press-fitted into bores 7 of their respective ends. The rods 6 are placed on cup-shaped receiving bores 8 in the beams 3 during assembly of the beams, the bores 8 being of slightly greater diameter than the diameter of the rods 6.

Secured to each of the cross arms 4 and 5 by rivets 9 are T-shaped brackets 10, 11, 12 and 13. The upper portion 14 of each of the brack-

2

ets encircles the periphery of the cross arms in each case. Brackets 10, 11, 12 and 13 have cylindrical lower portions 15 to receive legs 19. The legs are press-fitted into the cylindrical bracket portions, but rivets 20 are provided to assure a permanent retention therein.

Referring to Fig. 3, a leaf spring 25 is secured by screws 26 to beam 3. Arm 27 of the spring 25 includes a pawl 28 and a handle 29. 10 When the legs 19 are in the extended position the pawl 28 engages notch 31 in cross-arm 4, forming a positive lock therewith and preventing further rotation of cross-arm 4. The pawl 28 is manually disengaged from engagement 15 with notch 31 by merely pulling the handle 29 normally with regard to the cross-arm 4. The pawl 28 in a like manner engages a notch 30 in cross-arm 4 when the legs 19 are in the retracted position. Disengagement of pawl 28 with notch 20 30 is similar to the previously described extended leg condition.

A non-resilient rod 33 is used to interconnect cross-arms 4 and 5. The rod 33 is provided with oppositely curved end portions 34 and 35 to fit 25 about the portions of the periphery of cross-arms 4 and 5 adjacent to their respective points of attachment. The end portions 34 and 35 of the rod 33 are perforated to receive a pivot pin 36 which pivotally secures each end of said rod to brackets 37 on opposite sides of each cross-arm. The brackets 37 are secured to their respective cross-arms at such points as will permit a full retraction or extension of legs 19, without a contact resulting between either of 30 the end portions 34 and 35 and the cross-arms 4 and 5.

Operation of the invention is obvious from the drawings. By manually moving any one of the four legs 19 to the extended or retracted position, 40 after disengaging the locking mechanism, the other three legs are simultaneously moved to the same position. Thus in Figure 2 if any leg is moved from the extended position, the crossarms 4 and 5 will be moved counterclockwise and clockwise respectively by the rod 33 to simultaneously move the other legs to the retracted position. When the retracted position is reached by the legs, pawl 28 will engage notch 31 to lock the crossarm 4 against further rotation. The use of the oppositely curved end portions 34 and 35 on rod 33 gives the operating mechanism the necessary leverage to permit actuation of the legs and also provides an actuating means of this nature which may be con-

veniently hidden from view behind the sides 3 of an ordinary card table.

The rod acts as a lever arm between the cross-arms 4 and 5. The leverage system thus formed is not affected by the relatively short torque arm formed by the radius of the cross-arms, because the legs provide long lever arms and are also made of light weight material.

A table, therefore, is provided with a simple and economical means to cause complete and positive retraction or extension of the supporting legs by the mere actuation of any one of the legs.

I claim:

A table, two sets of paired legs for supporting the table, a crossarm of circular cross section forming a part of each set of paired legs and having an extended portion beyond said legs, means in the table to receive the extended portions of said cross arms and to rotatably carry said crossarms, a non-resilient rod having oppositely curved end portions substantially conforming to the curvature of the crossarms and disposed in a plane at right angles to the cross-arms, and a bracket secured to the periphery of each of said crossarms and positioned on op-

posite sides of a line connecting the longitudinal axes of the crossarms, one of said brackets pivotally supporting one end of said rod so that its curvature will conform to the crossarm curvature when the legs are extended, and the other bracket pivotally supporting the other end of said rod so that its curvature will conform to the curvature of the other crossarm when the legs are moved to the retracted position.
